Primary Examiner — Joseph Kukella*Assistant Examiner* — Darryl J Dardenne(74) *Attorney, Agent, or Firm* — Janeway Patent Law PLLC; John Janeway(57) **CLAIM**

The ornamental design for a coffee pot, as shown and described.

DESCRIPTION

FIG. 1 is a perspective view of a coffee pot showing my new design, according to an embodiment of the invention.

FIG. 2 is a front, elevation view thereof.

FIG. 3 is a rear, elevation view thereof.

FIG. 4 is a right, elevation view thereof.

FIG. 5 is a left, elevation view thereof.

FIG. 6 is a top, plan view thereof; and,

FIG. 7 is a bottom, plan view thereof.

The broken lines in the figures show portions of the coffee pot that do not form any part of the claimed design.
